LAWN MOWER HOUSING

William H. Huff, North Kansas City, Mo., assignor to Barnes Manufacturing Co., Inc., North Kansas City, Mo., a corporation of Missouri

Application July 20, 1954, Serial No. 31,505

Term of patent 14 years

(Cl. D40—1)

Fig. 1.

Fig. 2.

Fig. 3.

Fig. 4

To all whom it may concern:

Be it known that I, William H. Huff, a citizen of the United States, residing at North Kansas City, in the county of Clay and State of Missouri, have invented a new, original, and ornamental Design for a Lawn Mower Housing, of which the following is a specification, reference being had to the accompanying drawings, forming part hereof.

In the drawings:

Fig. 1 is a perspective view of a lawn mower housing showing my new design.

Fig. 2 is a plan view thereof.

Fig. 3 is a bottom view.

Fig. 4 is a side elevational view.

I claim:

The ornamental design for a lawn mower housing, as shown.
